UNITED STATES PATENT OFFICE

160,944

CHILD'S TROUSERS

Julian Herman, New York, N. Y.

Application December 30, 1949, Serial No. 6,928

Term of patent 7 years

(Cl. D3—17)

To all whom it may concern:

Be it known that I, Julian Herman, a citizen of the United States, residing in New York City, in the county of New York and State of New York, have invented a new, original, and ornamental Design for Child's Trousers, of which the following is a specification, reference being had to the accompanying drawing, forming part thereof.

Fig. 1 is a front view of child's trousers showing my new design,

Fig. 2 is a rear view thereof, and

Fig. 3 is a side view thereof.

The characteristic feature of my design resides in the portions shown on the drawing in full lines.

I claim:

The ornamental design for child's trousers, substantially as shown and described.

JULIAN HERMAN.
